UNITED STATES PATENT OFFICE.

FRANK D. LEWIS, OF WEST ORANGE, NEW JERSEY, ASSIGNOR TO PATHE FRERES PHONOGRAPH COMPANY, OF NEW YORK, N. Y., A CORPORATION OF DELAWARE.

AUTOMATIC STOP FOR VISIBLE RECORDS CORRESPONDING TO SOUND-RECORDS.

1,358,085.

Specification of Letters Patent.

Patented Nov. 9, 1920.

Application filed March 9, 1918. Serial No. 221,429.

To all whom it may concern:

Be it known that I, FRANK D. LEWIS, a citizen of the United States, and a resident of West Orange, county of Essex, and State of New Jersey, have invented certain new and useful Improvements in Automatic Stops for Visible Records Corresponding to Sound-Records, of which the following is a specification.

- 10 This invention relates to visible records adapted to have successive parts thereof exposed to view in synchronism with the reproduction of corresponding sounds by means of a phonograph. In this way sounds 15 may be heard at the same time that the visible characters or symbols, as words, are seen. With such apparatus the teaching and study of languages, music and the like may be greatly facilitated.
- 20 The phonograph, however, may continue running after the sound reproduction is completed and until stopped, and when the visible record is operated from the phonograph motor, as is most conveniently done, 25 the visible record may be injured or torn, or where a tape or ribbon is used to contain the visible record, its end may be pulled off the spool, thereby interfering with rewinding.

According to the present invention a ribbon or tape carrying the visible record, as printed words, notes or the like, is provided which may be operated in synchronism with the reproduction of sound from a phonograph record by means of a phonograph, 35 and which is so formed that it stops automatically at the proper point.

Where the tape or ribbon is provided with a series of holes for the reception of sprocket teeth of a feed roll, this result may be obtained by providing a blank space or cut-out or opening in the ribbon or tape, and when the same reaches the sprocket wheel as the ribbon or tape is unwound, there is nothing for the sprocket teeth to engage 45 and the sprocket wheel may revolve freely without producing further movement of the ribbon.

For the purpose of making my invention clearly understood, certain forms in which 50 it may be embodied are illustrated in the accompanying drawing. Figure 1 shows one form of my improved record ribbon with so much of the operating mechanism as is necessary for the understanding of the 55 operation of the apparatus. Fig. 2 is an

enlarged view of a portion of the ribbon shown in Fig. 1. Fig. 3 is a fragmentary view of a ribbon similar to that shown in Figs. 1 and 2 but with the omission of the reinforcing means, and Fig. 4 is a view of 60 a further modification.

The ribbon is designated by the numeral 10. When intended for use with a double faced record it may be provided with two lines of characters, as indicated by the two 65 lines of lettering marked 11 and 12, or the characters corresponding to the two sides of the sound record may be placed on opposite faces of the ribbon if desired.

The ribbon 10, as shown, is provided with 70 two series of perforations 13 and 14 near its edges which are adapted to be engaged by the sprocket teeth 15 of a feed roll 16. This feed roll may be operated from the phonograph motor, and the connection shown for 75 this purpose comprises a gear 17 on the feed roll 16 which meshes with the gear 18 on the shaft 19. The shaft 19 carries a bevel gear 20 which is driven from a bevel gear 21 on the shaft 22, which forms a part of or 80 is connected to a phonograph motor and turns at such speed that the sound characters of the ribbon 10 may be exposed to view as the corresponding sounds are reproduced from the phonograph or a phonographic record having a sound groove so recorded as to correspond to the visible 85 characters of the ribbon. Suitable means for winding up the slack of the ribbon delivered from the feed roll 16 may be provided, and the same may be operated as by 90 a belt from the pulley 23 on the feed roll shaft 16.

It will be seen that when the sprocket holes 13 and 14 are continued to the end of the ribbon without interruption, and the phonograph is continued to operate after the reproduction of the record is completed, it will be entirely unrolled from the spool 24 and may be torn or injured. In order to prevent this I provide the ribbon 10 with a cut-out or blank space 25 in line with the perforations 13 and 14, and when such cut-out or blank space is reached, preferably shortly after the longest series of visible characters, 105 as indicated in the present case at 12, has been exposed to view, the sprocket teeth 15 having nothing with which to engage, the feed roll 16 may continue to rotate without, however, advancing the tape or ribbon 10. 110

When the sprocket teeth 15 enter the cut-out or the blank space 25, the motion of the ribbon 10 stops and the phonograph may continue to operate while the ribbon 10 remains stationary. The perforations 13 and 14 may terminate at the cut-out 25, as there is no occasion for the provision thereof beyond the said cut-out or blank portion, but in practice the sprocket holes are preferably cut 10 on a machine operating continuously and may most readily extend the entire length of the tape or ribbon, and in the drawing the sprocket holes are so shown. It is to be noted, however, that the extra sprocket holes 15 between the blank space 25 and the end 10' of the ribbon serve no function and are present only for constructional reasons. The cut-out 25 is preferably at a sufficient distance from the end 10' of the spool 24 so 20 that when the cut-out reaches the feed roll, a portion of the ribbon is still wound on the spool 24, as shown in Fig. 1.

Where the ribbon 10 is of comparatively strong, tough material it is sufficient to 25 merely cut out the material for a distance of three or four of the sprocket holes, as shown at 25', Fig. 3, but preferably in order to avoid too greatly weakening the ribbon I provide it with a reinforce 26 about the 30 edges of the cut-out space 25, which reinforce may be of any appropriate material and secure it in place in any desired way, as, for example, the reinforce may be of fairly heavy paper or fabric, glued, cemented or 35 otherwise secured in place, and may be placed on one side of the ribbon, or, if desired, on both sides.

In Fig. 4 is shown a modification in which, instead of providing holes 25 in line with the 40 sprocket perforations 13 and 14, leaving the edges of the ribbon intact, the ribbon is provided with a cut-out 27 extending to the edges of the ribbon. With this construction somewhat more substantial reinforcing 45 means are desirable, and I may provide reinforcing plates 28 of flexible material which extend for a short distance along the ribbon and may have one or more of the sprocket holes 13 and 14 formed therein, and in the 50 form shown in Fig. 4 two of the feed perforations are contained in such reinforce 28.

The cut-out or blank spaces are preferably located at some distance from the end of the ribbon, as shown in Fig. 1, so that 55 the movement of the ribbon stops while the same is still attached to the spool 24, so that

upon being released from the feed mechanism it can be readily rewound thereon. On the other side of the reinforce 28 there is no need of sprocket openings, and those in the 60 tape 10 may be covered up, as indicated at 13' and 14', Fig. 4.

It will be seen that with a ribbon embodying the present invention an efficient and automatic stopping action at the proper 65 point can be readily and simply obtained without the necessity of resorting to complicated mechanical declutching means or the like.

I claim:

1. A ribbon having visible characters thereon having a series of substantially closely arranged sprocket holes near the edge thereof, a cut-out in the ribbon extending to the edge thereof and in line with the 75 perforations, and reinforcing means secured to the ribbon in the region of the cut-out.

2. A ribbon having two sets of visible characters, means whereby said ribbon is adapted to be engaged and fed along and its 80 successive parts exposed to view, and means located beyond the longest of the sets of characters for automatically terminating the movement of the ribbon after both sets of characters thereon have been exposed to 85 view.

3. A ribbon provided with a series of sprocket holes arranged substantially closely together and adapted to be engaged by a sprocket wheel, and having a cut out portion 90 in line with the sprocket holes and of length equivalent to the space occupied by a plurality of the sprocket holes, whereby the sprocket may turn freely when such opening is reached without actuating the ribbon, 95 so that the feed of the ribbon is thereby terminated.

4. A ribbon provided with two lines of sprocket holes and having two cut out portions, one in line with each of the sprocket 100 holes and opposite one another, said cut out portions being of length equivalent to the space occupied by a plurality of the sprocket holes, whereby the sprocket may turn freely when such openings are reached 105 without actuating the ribbon, so that the feed of the ribbon is thereby terminated.

In testimony that I claim the foregoing I hereto set my hand, this 27th day of February, 1918.

FRANK D. LEWIS.
